UNITED STATES PATENT OFFICE.

AUSTIN E. PERRY, OF WAKEFIELD, AND WILLIAM GORDON, OF BOSTON,
MASSACHUSETTS; SAID PERRY ASSIGNOR TO SAID GORDON.

LEATHER FORMING OR MOLDING MACHINE.

SPECIFICATION forming part of Letters Patent No. 564,641, dated July 28, 1896.

Application filed October 16, 1895. Serial No. 565,838. (No model.)

To all whom it may concern:

Be it known that we, AUSTIN E. PERRY, of Wakefield, in the county of Middlesex, and WILLIAM GORDON, of Boston, in the county of Suffolk and State of Massachusetts, have invented certain new and useful Improvements in Leather Forming or Molding Machines, of which the following is a specification.

10 This invention relates to machines for molding leather by pressure between two opposed surfaces, and it has particular reference to machines for making outer soles of spring-heel boots and shoes, such soles being offset 15 to form an incline between the heel and shank portions of the sole in a manner well understood.

The invention has for its object to provide an improved machine adapted to quickly and 20 effectively form the offset or inclined breast on a sole; and it consists in the improvements which we will now proceed to describe and claim.

Of the accompanying drawings, forming a 25 part of this specification, Figure 1 represents a front elevation of our improved machine. Fig. 2 represents a top plan view. Fig. 3 represents an end elevation. Fig. 4 represents a section on line 4-4 of Fig. 2. Fig. 5 represents 30 a partial elevation and partial section of portions of the machine, showing the operation of molding the sole. Fig. 6 represents a view similar to Fig. 5, the scoring device being omitted. Fig. 7 represents a sectional view of a portion of a sole as formed by the 35 improved machine. Fig. 8 represents a modification.

The same letters of reference indicate the same parts in all the figures.

40 In the drawings, *a* represents a supporting-frame having fixed bearings for a shaft *b*, to which is affixed a bed-roll *c*. Said bed-roll has two beveled peripheral surfaces 23, forming a groove, and a cylindrical peripheral surface 4 face 4 at one side of said groove.

45 *d* represents a yoke or frame which is mounted to oscillate upon pivots or centers *d* *d*' and is movable toward and from the shaft *b* and bed-roll *c*. The yoke *d* is provided with bearings in which is journaled a shaft *e*, to which is affixed an indenting-roll *f*, the periphery of

which has a milled or corrugated angular edge coinciding with the bottom of the groove in the bed-roll, the said indenting-roll being placed directly over the bed-roll, so that the 55 two are adapted to coöperate in bending a sole *s* in the manner shown in Figs. 5 and 6. The swinging movement of the yoke *d* enables the indenting-roll to be adjusted toward and from the bed-roll to accommodate any thickness of sole, an adjusting-screw *g* being engaged with a fixed nut *g*' on the supporting-frame and journaled at its lower end in a cavity in the yoke *d*, as shown in Fig. 4, said screw furnishing a convenient means for adjusting the yoke and holding it in any position to which it may be adjusted. The rolls *c* and *f* are positively rotated in the directions indicated by the arrows in Fig. 3 by any suitable means, such as a driving-shaft *h*, a pinion *i* thereon, a gear *j* on the shaft *b*, meshing with said pinion, and intermeshing gears *k* *k*', affixed respectively to the shafts *b* and *e*. 70

m represents a circular knife or scoring-disk which is located beside the indenting-roll and occupies such position that it cuts into or scores the upper surface of the sole along a line over the cylindrical portion 4 of the bed-roll, said portion supporting the leather under the pressure of the scoring-blade. 75

The object of the scoring-blade is to cut a transverse incision *s*' in the upper surface of the sole at one edge of the incline or offset *s*², formed by the conjoint action of the rolls *c* 80 and *f*, as shown in Fig. 5, said incision enabling the sole to be readily bent to form a reentrant angle at the upper edge of the breast or incline *s*² on the under side of the sole. The scoring-disk *m* is attached to a 85 holder *m*', which is mounted to rotate upon a stud *m*², secured to a vertically-adjustable slide or block *m*³, the stud *m*² being horizontally adjustable in said block, so that the scoring-disk can be adjusted horizontally toward and from the indenting-roll to vary the 90 distance between the incision *s*' and the bottom of the groove formed in the sole by the indenting-roll, and also adjusted vertically to vary the depth of the incision *s*' or to accommodate the scoring-disk to soles of different thickness. The horizontal adjustment 95 100

of the scoring-disk is effected by means of a screw-thread connection between the stud m^2 and the slide m^3 , a check-nut m^5 being employed to hold said stud at any point to which it may be horizontally adjusted. The vertical adjustment of the scoring-disk is effected by means of an adjusting-screw m^6 , having a screw-thread connection with the yoke d and journaled in the slide m^3 , so that when the screw is raised or lowered by its rotation it will impart a similar movement to the slide.

In order to provide for adjustment of the scoring-disk independently of the indenting-roll, we connect said disk and roll by means of a pin n , affixed to the disk and entering a slot o in the indenting-roll, said pin and slot constituting a self-adjusting connection which maintains an operative engagement between the roll and disk, so that the disk is positively rotated by the roll and permits independent adjustment of either the disk or the roll.

p represents a horizontally-movable slide or sole-carrier, which is movable in guides at right angles with the shafts of the rolls c f , the carrier being arranged at such height that a sole s , resting on its upper surface, will, by the movement of the carrier toward the left in Fig. 3, be presented to the rolls, which will grasp the sole and remove it from the carrier, the latter being loose and movable only by the operator. The carrier p is guided in its movement by the engagement of a tongue or projection p' on its under side with a groove p^3 , formed in the supporting-frame. (See Fig. 1.) The carrier is provided at one edge with a fixed gage p^3 , and at its opposite edge with a movable gage p^4 , the latter being pivoted at p^5 to the carrier and adapted to swing downwardly below the upper surface of the carrier, as indicated in dotted lines in Fig. 3, when it has passed the meeting points of the rolls c and f , the gage p^4 being permitted to thus drop by a depression p^6 on the supporting-frame. The gage p^4 is used when the soles of right boots and shoes are being treated, the outer edge of the sole bearing against the gage p^4 , as indicated in full lines in Fig. 2. During the inward movement of the carrier by the operator the gage p^4 remains in its operative position until the sole has been inserted between the rolls and then drops to the position shown in dotted lines just as the rolls commence to grasp and move the sole forward, so that the gage does not oppose the forward movement of the sole by the rolls.

When a left sole is being treated, its outer edge rests against the fixed gage p^3 , as indicated in dotted lines in Fig. 2, and is pushed onward by said gage until the sole is grasped and carried forward by the rolls, the gage p^4 dropping to permit the sole to be moved off from the carrier by the rolls.

q represents a heel-gage, which is adjustably mounted upon the carrier and bears on

the end of the heel of the sole s . Said gage has a graduated plate q' , which co-operates with a finger or pointer q^2 on the supporting-frame in indicating the position of the gage q for soles of different sizes.

The operation of the machine is as follows: In treating a right sole the operator places the sole upon the carrier, as indicated in full lines in Fig. 2, and pushes the carrier inwardly until the sole is grasped by the rolls, the gage p^4 at the same time dropping. The rolls grasp the sole and move it onward, indenting the same, as shown in Fig. 5, the heel end of the sole tipping upwardly. The sole is delivered by the rolls at the back of the machine. When a left sole is being operated on, the operation is the same as above described, excepting that the outer edge of the sole is placed against the fixed gage p^3 .

It will be seen that by the described apparatus soles can be quickly molded and adapted for use on spring-heel boots and shoes.

We do not limit ourselves to the use of the scoring-disk, as the rolls c and f , used without said disk, as indicated in Fig. 6, will mold or offset the sole, though not as perfectly as when the disk is used.

It is obvious that the machine may be adapted to other uses without departing from the spirit of the invention.

We do not limit ourselves to the particular details of construction here shown, and the same may be modified in various particulars. For instance, instead of providing two gages for the sole-carrier, a single gage may be used for both right and left soles, as in the modification shown in Fig. 8, in which p^8 represents a gage pivoted at p^9 to the carrier and adapted to occupy a position parallel with the shafts of the rolls for left soles, as shown in dotted lines, and to be placed diagonally or oblique for action on right soles, as shown in full lines, said gage being secured in either position by means of a clamping-nut p^{10} .

We claim—

1. In a machine of the character specified, the combination of a grooved bed-roll having a peripheral surface at one side of the groove, an indenting-roll arranged to enter the groove of the bed-roll, and a rotary scoring-disk located beside the indenting-roll in position to co-operate with the peripheral surface of the latter.

2. In a machine of the character specified, the combination of a grooved bed-roll having a peripheral surface at one side of the groove, an indenting-roll arranged to enter the groove of the bed-roll, a rotary scoring-disk located beside the indenting-roll in position to co-operate with the peripheral surface of the latter, and a connection between the indenting-roll and disk, whereby one is caused to rotate with the other.

3. In a machine of the character specified, the combination of a grooved bed-roll, an indenting-roll arranged to co-operate with the bed-roll, a scoring-disk located beside the in-

denting-roll, a support for said disk adjustable independently of the indenting-roll, and means for adjusting and holding said support.

4. In a machine of the character specified, 5 the combination of a supporting-frame, a grooved bed-roll, a yoke pivoted to the supporting-frame to swing toward and from the bed-roll, a shaft journaled in bearings in said yoke and provided with an indenting-roll, 10 means for holding said yoke in different positions, a support or bearing independently adjustable on said yoke, and a scoring-disk on said support.

5. In a machine of the character specified, 15 the combination of a grooved bed-roll, an indenting-roll arranged to coöperate with the bed-roll, means for positively rotating said rolls, a scoring-disk located beside the indenting-roll and adjustable independently thereof, and a self-adjusting connection between the indenting-roll and the scoring-disk through which the disk receives motion from the roll.

6. In a machine of the character specified, 25 the combination of a bed-roll having two beveled peripheral faces forming a groove, and a cylindrical peripheral face 4 at one side of the groove; an indenting-roll having an angular periphery coinciding with the bottom of said 30 groove; and a scoring-disk located beside the

indenting-roll and over the face 4 of the bed-roll.

7. In a machine of the character specified, the combination of a grooved bed-roll, an indenting-roll, and a sliding sole-carrier having 35 means for supporting either right or left soles in proper relation to said rolls.

8. In a machine of the character specified, 40 the combination of a grooved bed-roll, an indenting-roll, a supporting-frame, a sole-carrier movable on said frame and having at one edge a movable guide and at its opposite edge a fixed guide, and means whereby the movable guide is displaced at a given point in the movement of the carrier. 45

9. In a machine of the character specified, the combination of a grooved bed-roll, an indenting-roll, a sliding carrier having means for supporting either right or left soles in proper relation to said rolls, and an adjustable 50 gage for the heel end of a sole.

In testimony whereof we have signed our names to this specification, in the presence of two subscribing witnesses, this 9th day of October, A. D. 1895.
